UNITED STATES PATENT OFFICE.

JAMES E. HITCHCOCK, OF TORRANCE, CALIFORNIA.

SUCKER-ROD HANGER.

Application filed November 17, 1924. Serial No. 750,324.

My present invention is referred to as a sucker rod hanger, for the reason, that although this device may be used in various connections, it is a primary object of this invention to provide means for the support of the comparatively long sections or "stands" of sucker rod within an oil well derrick, or the like.

Incidentally to the withdrawal of a string of tubing from a producing well, it is customary to separate the string into comparatively long stands, which are ordinarily elevated into and supported by the derrick frame. As each section or stand of tubing is separated, some disposition must be made of the sucker rod which has previously extended through the same. It has been common to lay the sections or stands of sucker rod upon the ground; but in this position they are liable to accidental damage, and it has accordingly been proposed to employ a separate grab hook for the engagement of the coupling upon the upper end of each section or stand of rod, thereby holding the same separately in an upright position, in a manner somewhat similar to the mentioned disposal of stands of pipe or tubing. It is an object of this invention to improve upon the last mentioned method of supporting sections or stands of rod; and a preferred embodiment of my invention may comprise means for separately supporting a considerable number of rods or rod sections from a single intermediate element suspended from a primary support at the top of a derrick.

It is a further object of this invention to provide a swivel or rotative connection at some point between a primary support and a circular plate, or the like, with which a plurality of rod grabs may be flexibly connected.

It is a further object of this invention to provide an improved type of rod grab; and each of my grabs may comprise a cooperating pair of roughened elements, easily engageable or disengageable, which are adapted automatically to grip even a smooth intermediate portion of a rod, or the like.

Other objects of my invention will appear from the following description of an advantageous embodiment thereof, taken in connection with the appended claims and the accompanying drawings, in which

Fig. 1 is an elevational view, with parts broken away, showing the general manner

in which my invention may be used in the supporting of sucker rods, or the like.

Fig. 2 is a vertical sectional view on an enlarged scale, showing a preferred type of grab, a preferred type of intermediate element, and preferred types of connecting and intermediate elements.

Fig. 3 is a separate elevational view of a single rod grab, showing in full lines the relative positions which parts may occupy at the time when a rod is being engaged or disengaged, dotted lines being employed to show the same parts in a gripping position.

Fig. 4 is a horizontal sectional view taken substantially as indicated by the line 4-4 in Fig. 1.

Referring to the details of that specific embodiment of my invention chosen for purposes of illustration, 11 being a derrick frame, or the like, of which a top element 12 may be adapted to serve as a primary support, each section of rod, as it is removed from a well, may be carried as by an elevator, not shown, to substantially the position indicated at 13 in Fig. 1; and, upon its arrival at this elevated position, a workman remaining in a suitably elevated position may insert the same between a pair of cooperating engaging elements 14, 14', serving as open jaws and shown as supported upon the free end of a bent bar 15, constituting the body of an individual grab, in such manner as to admit a rod by a lateral relative movement.

Although grabs of the general character illustrated might be individually supported, as by means of chains or other flexible fastening elements extending separately to the primary support 12, or its equivalent, I consider it advantageous to employ separate fastening chains 16, which may be secured at their lower ends to the respective grabs, as by means of eyes, 17, the upper end of each chain being shown as secured by an eye-bolt 18 to a disc-like intermediate supporting element 19, which may be in the form of a substantially circular plate adapted to carry a considerable number, as, for example, 50 grabs of the general character described, these being shown as open-jaw grabs attached in concentric rows.

The intermediate support 19, or its equivalent, may be connected to the primary support, as by a swivel or rotative connection comprising a ball bearing 20, interposed between a nut 21 and said intermediate sup-

port. The connecting hook 29, or its equivalent, may be supported directly from a primary support, or it may be suspended therefrom by means such as a chain or other loop 22; and means such as a cord 23, preferably extending through an eye 24, may be employed to prevent an accidental displacement of the hook 21, or its equivalent, from the chain 22.

- 10 The mentioned rod engaging elements 14, 14' may be of any preferred character; but I prefer to provide these elements shown as substantially circular in cross-sectional outline, with slightly concave corrugated lateral surfaces and to mount the same eccentrically but rotatively upon pins 25, 25', or their equivalent, and to space the said engaging elements apart sufficiently to permit the free insertion of a rod 26, therebetween.
- 15 20 The weight of the rod may then be effective to cause a gripping engagement thereof, substantially as illustrated by dotted lines in Fig. 3.

It will be obvious that, in the use of an organization of the general description described, the engagement of each rod is direct and independent of any contact between the grab and any coupling element upon the end of the rod. Each rod may be readily brought into a position of engagement by a lateral movement, and may be promptly gripped, without requiring to be manually levelled. The freedom of rotative movement of the intermediate support 19, shown as confined between the mentioned ball bearing 20 and a collar 27 at the base of the connecting hook 29, is such as to facilitate the bringing of each and all of the grabs in turn into an advantageous position of use. The disengagement of each rod, as may be required in the restoration of the same into a position of use, can obviously be advantageously effected by the mere elevation of the same followed by a slight lateral movement. The entire organization is simple, rugged, and reliable, and it is found notably to facilitate and expedite the handling of sucker rods, or the like; and means such as a chain 28 may be employed to secure an entire bundle of rods in an out of the way position.

Although I have herein described a single complete embodiment of my invention, it will be understood that various features thereof might be independently employed,

and that also various modifications might be made, by those skilled in the art to which this case relates, without the slightest departure from the spirit and scope of my invention, as the same is indicated above and in the following claims.

I claim as my invention:

1. A hanger for rods, or the like, comprising; a disc-like intermediate element provided with means for connecting the same to a primary support and having an uninterrupted edge; a plurality of open jaw rod grabs; and flexible means below said disc-like element for securing said grabs separately to said intermediate element while permitting relative movement therebetween.
2. In a hanger as defined in claim 1, connecting means in the form of an open hook provided with an eye.
3. In a hanger as defined in claim 1, in which said intermediate element has the form of a plate adapted to support a plurality of grabs suspended therefrom in separate rows.
4. In a hanger as defined in claim 1, in which said intermediate element has the form of a plate supported between a collar and a bearing on said connecting means and carrying a plurality of rows of eye-bolts to which open-jaw grabs are secured by flexible means.
5. In a hanger as defined in claim 1, an open-jaw grab comprising a pair of cooperating eccentric roughened engaging elements substantially circular in cross-sectional outline and rotatively mounted on projecting pins.
6. In a hanger as defined in claim 1, an open-jaw grab comprising a pair of cooperating roughened engaging elements substantially circular in cross-sectional outline and rotatively and eccentrically mounted on pins on a bent bar provided with flexible means for its attachment.
7. In a hanger as defined in claim 1, an open jaw grab comprising a pair of cooperating roughened engaging elements centrally concaved and rotatively mounted; a plurality of grabs being flexibly secured beneath an intermediate plate also rotatively mounted.

In testimony whereof, I have hereunto set my hand at Los Angeles, California, this 10th day of November, 1924.

JAMES E. HITCHCOCK.
